CLAIM

The ornamental design for a pillow sleeve, as shown and described.

DESCRIPTION

FIG. 1 is a perspective view of a pillow sleeve, showing my new design within an environment of use;

FIG. 2 is a perspective view of a pillow sleeve;

FIG. 3 is a top plan view thereof, with the bottom plan view being identical thereto; and,

FIG. 4 is a front elevation view thereof, with the rear elevation being identical thereto.

In FIG. 1, the broken lines depict environmental subject matter that forms no part of the claimed design.

1 Claim, 2 Drawing Sheets
